UNITED STATES PATENT OFFICE

2,510,331

NUMBER OR LETTER CARRYING DEVICE

Edward A. Crosby, Minneapolis, Minn.

Application November 8, 1946, Serial No. 708,495

6 Claims. (Cl. 40—140)

1

This invention relates to an improved structure system or method of assembling and holding members carrying thereon letters, numbers, designs, symbols or other characters. Letters, numbers and characters, or combinations thereof, are now used in many places to designate various objects and are used in many places and for many purposes, such as for automobile license plates, house numbers, street and other signs, name plates for offices, institutions, estates, railway cars, etc. Where a large number of similar signs or plates are to be used, it is desirable to have a structure of neat and pleasing appearance in which the desired combinations can be easily and quickly secured and assembled in one unit, said unit preferably comprising a plate or plates having a flat surface engaging the supporting surface and being capable of being easily maintained in proper and permanent position.

It is an object of this invention to provide an extremely simple and highly efficient assembly of numbers, letters and other characters which can be easily and quickly put together and which will be durable and securely held in assembled position.

It is another object of the invention to provide such an assembly comprising a holder plate and one or more character plates, said holder plate being constructed and arranged to receive the character plates so that the desired character plate or plates may be easily and quickly placed in position in the holder plate, said plates having cooperating parts for holding the same in proper and assembled position. Character plates may carry one or more characters and these may be of the same or different sizes and said holder plate is preferably constructed so as to fit flat against a supporting surface.

It is a further object of the invention to provide a letter, number or symbol assembly device comprising a holder plate which preferably has an outer portion disposed in substantially the same plane and which has embossed or outwardly pressed portions within said outer portion forming one or more panels, said panels having a lower substantially horizontal surface having a slot extending therethrough, together with a character plate for each of said panels adapted to be brought into position substantially parallel to said holder plate and in close proximity thereto, said character plate having a tongue at its bottom adapted to be received in said slot and having shoulders adapted to be supported upon said horizontal surface, the top portion of said character plate being held in position by said embossed portion.

2

It is more specifically an object of this invention to provide a letter and/or number assembly device comprising a holder plate having an outer portion disposed substantially in the same plane and having an embossed or outwardly pressed portion formed thereon within said outer portion, the same preferably being continuous so as to form one or more panel-like parts, each of which has a lower horizontal surface with a slot extending vertically therethrough and transversely thereof, said holder plate having an opening therethrough adjacent the top of each of said panel parts, together with a character plate adapted to carry letters, numbers or symbols, the same being of a width to fit in said panel parts and to extend through said opening in said holder plate, said character plate having a tongue at its bottom adapted to be received in said slot and having shoulders at the sides of said tongue adapted to be supported on said horizontal surface, the top of said character plate being held in position by the top part of said embossed portion.

These and other objects and advantages of the invention will be fully set forth in the following description made in connection with the accompanying drawings in which like reference characters refer to similar parts throughout the several views and in which:

30 Fig. 1 is a view in front elevation of the device, one character plate being omitted;

Fig. 2 is a vertical section taken on line 2—2 of Fig. 1;

Fig. 3 is a vertical section taken on line 3—3 of Fig. 1;

Fig. 4 is a horizontal section taken on line 4—4 of Fig. 1;

Fig. 5 is a view in front elevation of a character plate used;

40 Fig. 6 is a vertical section taken on line 6—6 of Fig. 5;

Fig. 7 is a partial perspective view of a holder plate used;

Fig. 8 is a vertical section taken on line 8—8 of Fig. 7, all of said sections being taken as indicated by the arrows;

Fig. 9 is a view in front elevation of a modified form of the device;

Fig. 10 is a view in front elevation of another modification;

Fig. 11 is a perspective view showing how a character plate may be removed; and

Fig. 12 is a view similar to view 11 showing how the character plate may be swung out of the holder plate.

Referring to the drawings, a device is shown

comprising a plate 20. Said plate will be designated as a holder plate, and while the same could be made in various shapes to suit various conditions, in the embodiment of the invention illustrated it is shown as substantially rectangular with rounded corners. Plate 20 has an outer portion 20a extending thereabout and which is disposed in substantially one plane. A bead 20b is formed in portion 20a and pressed outwardly, the same extending about plate 20 substantially parallel to the edge thereof and being substantially semi-circular in transverse cross section. Plate 20 is shown as having a plurality of holes 20c extending therethrough and while these might be variously disposed they are shown as four in number and located at the corners of the plate within bead 20b. Within the portion 20a, plate 20 has an embossed or outwardly pressed portion 20d. While portion 20d might take various forms, in the embodiment of the invention illustrated it is shown as substantially rectangular with slightly rounded corners and the sides thereof are parallel to the edges of plate 20. Portion 20d has narrow side portions 20e between which are narrow intermediate dividing portions 20f. The bottom of portion 20d is also of small transverse dimension vertically and said bottom portion has a top horizontal surface 20g between the portions 20e and 20f in which is formed a slot 20h which extends vertically through said horizontal portion 20n and transversely thereof, said slot being of less length than the distance between the adjacent portions 20f and 20e. The top part of embossed portion 20d is shown as of somewhat greater transverse dimension vertically than the bottom portion and apertures 20j are formed in plate 20 immediately below said top portions in the spaces between portions 20e and 20f. The portions of plate 20 between the top and bottom parts of portion 20d and between the adjacent portions 20e and 20f could be designated as panels. These portions 20i are disposed in the same plane as portion 20a. The lower edge of the top part of portion 20d is pressed outwardly in substantially semi-spherical form so as to constitute a cup-like projection or socket 20k and each of these is located preferably in the center of one of said panels. An aperture 20m, shown as of elongated rectangular form, is formed through plate 20 in each of said panels and said apertures are disposed substantially centrally transversely of each panel.

A number of character plates 21 are provided and these will carry characters, such as numerals, letters or symbols. In the embodiment of the invention illustrated, these plates are shown as carrying numerals 21a, and while these could be variously formed on or attached to the plate, they are shown as being embossed or pressed outwardly therein. Each plate 21 is of a width slightly less than the width of one of said panels and is of a length greater than the distance between the horizontal surface 20g and the bottom edge of the top part of portion 20d. Each plate 21 is provided at its bottom with a projecting portion or tongue 21b shown as having downwardly sloping sides and as being of considerable less width than the width of said plate. Shoulder portions 21c are thus formed at the bottom of plate 21 at each side of tongue 21b. Plate 21 adjacent its top edge and preferably centrally thereof is provided with an embossed or outwardly pressed portion or lug 21d, shown as substantially semi-spherical in shape.

With the described construction plate 20 can be provided with three of the plates 21 and an assembly is produced forming a sign, marker or other designation for the particular object to be marked. Any three digit number can be produced and any three part combination of letters, numbers or symbols. Plate 21 will have its top portion inserted through aperture 20j from the front of plate 20 and plate 21 will then be swung toward plate 20 at its lower portion and brought into position substantially parallel to plate 20. Tongue 21b will be inserted in the slot 20h and the shoulders 21c will then rest on surface 20n at each end of slot 20h. The lug 21d on plate 21 will now fit into the socket 20k on plate 20, as clearly shown in Fig. 2. This will prevent lifting or upward movement and removal of plate 21. Many automobiles are stolen and the license numbers changed. The lug and socket structure will make it difficult to remove and change the numbers. Plate 21 is now nicely disposed in plate 20 and will be held snugly therein. When the device is thus assembled it can be attached to the article, structure or object to be marked by being placed thereagainst and held by fastening means, such as nails or screws inserted through openings 20c.

In Fig. 9 a plate 25 is shown of elongated rectangular form with rounded corners and this plate 30 has an outer portion 25a extending thereabout which is disposed in substantially one plane. This portion has a bead 25b similar to bead 20b extending thereabout and substantially parallel to the edge of plate 25. Holes 25c for attaching means are formed through plate 25 and are shown as disposed at the corners thereof within bead 25b. Plate 25 has an embossed or outwardly pressed portion 25d within portion 25a, which embossed portion has side parts 25e of narrow transverse dimension and has bottom and top parts 25f and 25g respectively. Portion 25f has a top horizontal surface in which is formed a slot similar to slot 20h already described. An aperture 25j is formed through plate 25 immediately 35 below the portion 25g, which aperture extends between parts 25e. The bottom part of portion 25g is pressed outwardly to form a semi-spherical cup-like projection 25h. An aperture 25m, similar to aperture 20m, is shown and this extends 40 through the portion 25i of plate 25, which is disposed between portions 25e and between top and bottom portions 25f and 25g. The number plate 21 is used with plate 25 and it will be inserted and held therein in the same manner as already 45 described with plate 20. The plate 25 can be used where only one numeral, letter or symbol is desired in the device.

In Fig. 10 an elongated plate 28 is shown and this has an outer portion 28a extending thereabout and disposed in one plane within which is formed an outwardly projecting bead 28b extending parallel to the edge of plate 28, which bead is similar to bead 20b already described. Plate 28 is also shown as substantially rectangular in 50 form with rounded corners. An embossed or outwardly pressed portion 28c is formed in plate 28 and this has vertically spaced side parts 28d of narrow transverse dimension, a bottom part 28e of small transverse dimension vertically, a top part 28f having a transverse dimension vertically somewhat larger than bottom portion 28e. Portion 28c also has spaced horizontally extending portions 28g. Bottom portion 28e and portions 28g have top horizontal surfaces 28h in which are 55 formed slots similar to slot 20h. The bottom edge

part of portions 28f and 28g are provided with outwardly pressed semi-spherical projections 28i similar to projections 29k and 25h. Plate 28 also has apertures 28j extending therethrough immediately below the lower edge portions of portions 28f and 28g, which apertures extend between side portions 28d. Apertures 28k, similar to apertures 20m, are formed through plate 28 in the panel portions 28m, which panel portions are in the same plane as outer portion 28a. Plate 28 is also provided with holes 28n at its top and bottom through which fastening means will extend. Character plates 21 will be used with plate 28 and these will be inserted in said plate in the same manner as already described in connection with plate 20. Plate 28 is used where it is desired or more convenient to have the numerals, letters or symbols arranged vertically. Such a plate could be used when a device is used on poles, such as telegraph or telephone poles, or when some vertically elongated object is to be marked. There is often not room on buildings, panels and other structures for a wide plate such as plate 20.

When the device is removed from its support and it is desirable to remove the character plate therefrom, this can be done as illustrated in Figs. 11 and 12. The device can be held in one hand and character plate 21 can be pushed upwardly by a tool or implement 29 held in the other hand of the operator and pressed against the bottom of tongue 21b. When said tongue is moved through slot 20h or similar slot, the implement 29 can then be inserted through aperture 25m or a similar aperture and plate 21 pushed forwardly, as shown in Fig. 12. Plate 21 can then be easily withdrawn from opening 25j or a similar opening.

From the above description it will be seen that I have provided a simple, improved and highly efficient letter, number or symbol assembly device which can be used for marking, naming or designating various objects, buildings and other structures and various articles. The device can also form an efficient sign. The desired designation can be easily and quickly formed, whether it be one letter, number or symbol, or a plurality of the same. Obviously various combinations of letters, numbers and symbols can be easily formed. When the device is secured against the surface of the object, the holder plate fits closely against the surface around its entire edge portion. A tight fit can thus be had which will exclude water, snow, insects, etc.

The present device is an improvement on that shown in applicant's Patent No. 2,342,847, granted February 29, 1944. The present device, as stated, gives a tight fit against the supporting surface and an efficient seal can thus be had entirely around the holder plate. The present device is also of easier manufacture than that shown in the said patent. The bead on the holder plate can be made continuous and this gives a much better looking device. It is not necessary to have any opening extend through the horizontal portion of the top part of the embossed portion of the holder plate. It will be noted that opening 20j and the corresponding openings in the other modifications extend only through the part of the holder plate which is in the same plane as the outer portion thereof. The present structure is quite an improvement on that shown in the said patent and constitutes a distinct advance in the art.

The device is particularly adapted for automobile license plates, house numbers, street design-

nations, telephone, telegraph and other pole numbers, name plates for offices, buildings, estates or institutions and for railway cars and other vehicles and structures. The device can be made in various sizes to suit the particular object or article to be marked. The dealer or other person handling the device can have the necessary character plates and holder plates in stock and these can be quickly and easily assembled to give the desired combination. The characters on the character plates can be painted or coated as desired and the surface of the holder plate will be suitably painted, enameled or coated to give a pleasing effect. It will often be desirable to have the letter, number or symbol on the character plate of a color contrasting to that of the holder plate. The beads 20b, 25b and 28b are of greater height than the embossed portions so that water can drip therefrom outwardly of the character plates and embossed portions. The parts of the device can be easily, simply and quickly made and the device is admirably suited for mass production. The device has been amply demonstrated in actual practice and found to be very successful and efficient.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A number or letter carrying device having in combination, a holder plate having an outer portion extending thereabout disposed substantially in one plane, a portion embossed to extend outwardly within said outer portion, and a portion within said embossed portion disposed substantially in said plane so that said embossed portion is of comparatively small transverse dimension the bottom part of said embossed portion having a substantially horizontal surface with a narrow slot extending transversely thereof and vertically therethrough, said plate having an opening therethrough adjacent the top of said last mentioned portion and a rigid character plate of longer dimension than the distance between said top surface and the top of said opening, said character plate being of smaller transverse dimension than said opening and having a tongue at its lower end of less width than the width thereof thus forming shoulders at the sides of said tongue, said character plate being adapted to be inserted through said opening at an angle to said holder plate and then moved into substantially parallel relation to said holder plate and closely adjacent said last mentioned portion and moved downwardly to bring said tongue into position in said slot with said shoulders supporting said plate on said horizontal surface and the top of said plate held by the top part of said embossed portion.

2. The structure set forth in claim 1, said holder plate having an outwardly pressed portion adjacent said opening and said character plate having an outwardly pressed portion adjacent its top adapted to fit in said last mentioned portion so that said character plate can be disposed in the rear of said last mentioned embossed portion.

3. A number or letter carrying device having in combination, a plate of general rectangular form having an outer portion extending there-

about and disposed in substantially one plane, an outwardly embossed portion within said outer portion having outer sides substantially parallel to the sides of said plate and a third portion within said embossed portion disposed substantially in said plane and having its sides parallel respectively to the sides of said plate whereby said embossed portion forms a rectangular frame of comparatively small transverse dimension, said embossed portion having a top horizontal surface at its bottom portion with a narrow slot extending transversely therethrough, said plate having an opening extending therethrough adjacent the top of said third portion, and a rigid character plate of less width than the width of said opening and of greater length than the distance between said horizontal surface and the top of said opening, said character plate having a tongue formed at its bottom of less width than said character plate thus forming shoulders at its sides whereby said character plate can be inserted through said opening and then brought into position substantially parallel to said holder plate and substantially against said third portion and said tongue disposed in said slot so that said character plate is supported on said horizontal surface and its upper end is disposed in the rear of the top part of said embossed portion.

4. A number or letter carrying device having in combination, a holder plate having an outer portion extending thereabout disposed substantially in one plane and having a portion embossed to extend outwardly within said outer portion, said embossed portion having spaced side portions of narrow width and top and bottom portions of comparatively small transverse dimension thus leaving a panel portion within said embossed portion disposed in substantially the same plane as said outer portion, said holder plate having an opening therethrough extending across said panel portion adjacent the top thereof, said bottom portion having a top surface with a narrow slot extending therethrough and transversely thereof and a character plate bearing a character thereon and of less width than said panel portion and having a tongue at its bottom of less width than said character plate whereby said character plate can have its upper end passed through said opening, then moved into position substantially parallel to said holder plate and lowered to dispose said tongue in said slot so as to rest on said top surface and be held in the

rear of said top portion of said embossed portion at its upper end and be disposed in said embossed portion above said panel portion.

5. The structure set forth in claim 4, said holder plate having a bead pressed outwardly therefrom in said outer portion extending thereabout between said embossed portion and the edge of said holder plate, said bead being of greater height than said embossed portion.
- 10 6. A number or letter carrying device having in combination, a holder plate having an outer portion extending thereabout disposed substantially in one plane and having a portion embossed to extend outwardly within said outer portion, said embossed portion having spaced side portions of narrow width and top and bottom portions of comparatively small transverse dimension, and also having spaced vertically extending portions extending between said top and bottom portions thus leaving panel portions between said side portions and vertically extending portions and between said top and bottom portions disposed in substantially the same plane as said outer portion, said bottom portion having top horizontal surfaces with slots extending therethrough and transversely thereof centrally of said panel portions, respectively, said panel portions each having an opening extending therethrough throughout the width thereof and adjacent the tops thereof and a character plate for each of said panel portions bearing a character thereon and of less width than said panel portion and having a tongue at its bottom of less width than said character plate whereby said character plate can have its upper end passed through one of said openings, then moved into position substantially parallel to said holder plate and substantially against the front of said panel and lowered to dispose said tongue in one of said slots so as to rest on said top surface and be held in the rear of said top portion, or one of said transverse portions.

EDWARD A. CROSBY.
